CONVEYER DEVICE

Charles G. O'Hara, Norristown, Pa., assignor to
Norristown Foundry Company, Inc., Norristown, Pa., a corporation of Pennsylvania

Application March 6, 1933, Serial No. 659,676

5 Claims. (Cl. 198—141)

This invention is particularly designed for inclusion in automatic stokers of the general character described and claimed in my copending application Serial No. 618,148 filed June 20, 1932, for Letters Patent of the United States. In such stokers, the ashes are elevated in a casing inclosing an endless chain with bucket conveyers which deliver the ashes to a lateral opening in the casing through which the ashes are discharged into a can or other removable receptacle. It was found in practice that such receptacles are sometimes left in such relation to the discharge opening from the conveyer casing that the ashes piled up on top of the receptacle and obstructed said opening. Therefore, in the construction shown in said copending application, I provided a Y-fitting in connection with the discharge opening from the conveyer casing adapted to discharge the ashes into two adjoining cans or receptacles, and provided that Y-fitting with a safety opening and a door for the same so that if and when the normal discharge opening from the conveyer casing became obstructed by ashes owing to the neglect of the operator to remove the can or cans, the pressure of the ashes upon said safety door would open the latter and discharge the surplus ashes aside from the cans. However, in practical experience with that construction and arrangement, I find that in cases of neglect to remove the ash receptacles at the proper time during the continued operation of the stoker, the ashes which accumulate in the Y-fitting partly fall back into the conveyer casing, thus imposing a loss of energy in the repeated uplifting of such surplus ashes, and that if the ashes become damp, as frequently occurs from wheather conditions, the force of gravity of the ashes against said safety door is sometimes insufficient to open the latter because of the coherence of the moist ashes, and the conveyer casing becomes clogged with ashes from top to bottom.

Therefore, the purpose and effect of my present invention is to provide means to prevent the return of ashes into said conveyer casing, through the opening from which they have been discharged toward the receptacle and if surplus ashes accumulate outside of said discharge opening between it and the safety door, to impose upon such surplus ashes mechanical pressure in addition to the gravitational force thereof to insure the opening of the safety door. After considerable experimentation, I have been able to devise a single movable element to accomplish both of those purposes, said element consisting of a single cast-

ing suspended from a pivot at its top, having a deflecting plate at its lower end and a lever arm extending from said pivot to said plate of such configuration as to be encountered by the outer edge of each of the buckets as the latter successively approach said discharge opening in the conveyer casing with the effect of oscillating said casting upon its pivot and imposing pressure from the buckets through said lever and deflecting plate upon the ashes outside of the latter.

My invention includes the various novel features of construction and arrangement herein-after more definitely specified.

In said drawing, Fig. I is a fragmentary elevation of the discharge side of the conveyer casing.

Fig. II is a vertical sectional view taken on the line II, II, in Fig. I through said casing and its appurtenances.

In said figures, the conveyer casing 1 is conveniently inclined upwardly and outwardly from the ash elevator base of the stoker in which the ashes are deposited. Said casing incloses the endless conveyer chain 2 which is conveniently hung upon sprocket wheels 3 and 4 respectively provided with shafts 5 and 6 at the bottom and top of said casing. Said shaft 5 is provided with any suitable means to turn it to progress the chain in the direction of the arrow indicated in Fig. II. Said shaft 6 is conveniently mounted in the inverted U-shaped bearing frame 8 which is mounted for adjustment, in the direction of length of the chain, in the slideway 9 in the elevator casing 1 and is continually stressed upwardly by the spring 11. As indicated in Fig. II, said spring 11 encircles the plunger 12, which is rigidly connected with said bearing frame 8 and bears at its lower end upon the removable cover 13 of said elevator casing 1, and bears at its upper end against the abutment plate 15 which encircles said plunger 12 and is adjustable by the nut 16 which engages a screw thread on said plunger. I find it convenient to provide said spring 11 and its appurtenances with the removable dust cap 17 which detachably engages the upwardly extending flange 18 on said cover 13.

Said chain 2 carries a series of buckets 20 for lifting the ashes to be conveyed and discharging them through the discharge opening 21 in the side of said conveyer casing 1. I prefer to provide said discharge opening with the Y-fitting 22 in connection with said casing 1 and adapted to discharge the ashes through its pendent branches 23 and 24 into adjoining cans or receptacles. As indicated in Fig. I, said branches 55

may be provided with respective flexible conduits 25 and 26 for extension to said receptacles. Said Y-fitting 22 has the safety opening 27 above and between said branches with any suitable means, for instance, the studs 29, for supporting a safety door 30 which normally closes said safety opening and which is preferably connected with said Y-fitting by the flexible connector 31 so that said door will not be lost in the discharged ashes, if and when said door is dislodged from its supporting studs to permit the ashes to be discharged through said safety opening aside from the receptacles to which the ashes are normally discharged through said branches.

The lever 32 has its upper end fulcrumed upon the pivot 33 which is conveniently a bolt extending through said casing 1, having the head 34 exterior to one side of said casing and the nut 35 exterior to the other side of said casing. Said lever has the deflecting plate 38 at its lower end extending obliquely adjacent the lower end of said discharge opening 21, and the counterbalance weight 39 on said lever is so proportioned and located as to normally maintain said deflecting plate in the position shown in Fig. II with the inner cam edge 41 of said lever extending in the path of the outer edges of said buckets 20. In that normal position, said deflecting plate insures that all of the ashes dumped from said buckets shall be deflected outwardly through said discharge opening 21 instead of partly falling back within said casing 1. Consequently, said lever is adapted to be encountered by said buckets in succession with the effect of thrusting it outwardly through said discharge opening 21 and against any surplus ashes which may accumulate in said Y-fitting, with the effect of imposing upon such surplus ashes mechanical pressure in addition to the gravitational force thereof to insure the opening of said safety door 30 under the abnormal conditions above contemplated.

Although I find it convenient to provide said discharge opening with the Y-fitting above described, having two branches for discharge of ashes into respectively separate receptacles, the construction and arrangement above described would be efficacious for the purpose contemplated if said fitting had but one branch; or, if there were no fitting exterior to said discharge opening, said lever would be operative to insure the deflection of the conveyed ashes outwardly from said casing 1 through said discharge opening 21.

Therefore, I do not desire to limit myself to the precise details of construction and arrangement herein set forth, as it is obvious that various modifications may be made therein without departing from the essential features of my invention, as defined in the appended claims.

I claim:

1. In a conveyer device, the combination with a casing having a discharge outlet at one end thereof; of an endless chain conveyer mounted in said casing; means for supporting and driving said chain, including sprocket wheels in the end bights thereof; a series of buckets on said chain for dumping the material conveyed through said discharge opening; a lever having a fulcrum at one end and a deflecting plate at the other end; means for supporting said fulcrum in said casing with said deflecting plate adjacent the lower end of said discharge opening; a counterbalance weight on said lever for normally maintaining

said deflecting plate in a predetermined position with respect to said discharge opening and the path of traverse of the buckets on said chain; said lever having a cam surface presented toward said chain and adapted to be encountered by said buckets in succession; a discharge fitting on said casing in registry with said discharge opening and having a safety door in the outer wall thereof; whereby operation of said chain causes the material discharged by said buckets to be deflected from said casing through said opening, and the successive contact of the buckets with said lever cam intermittently thrusts said deflecting plate through said discharge opening and permits it to be returned to normal position by said counterweight; and said safety door is thrust open to discharge exterior to said fitting any surplus conveyed material detained in said fitting.

2. In a conveyer device, the combination with a casing having a discharge opening at one end thereof; of an endless chain conveyer mounted in said casing; means for supporting and driving said chain; a series of buckets on said chain for dumping the material conveyed through said discharge opening; a lever having a fulcrum at one end and a deflecting plate at the other end; means for supporting said fulcrum in said casing with said deflecting plate adjacent the lower end of said discharge opening; means on said lever for normally maintaining said deflecting plate in a predetermined position with respect to said discharge opening and the path of traverse of the buckets on said chain; said lever being adapted to be encountered by said buckets in succession; a discharge fitting on said casing in registry with said discharge opening and having a safety door; whereby operation of said chain causes the material discharged by said buckets to be deflected from said casing through said opening, and the successive contact of the buckets with said lever intermittently thrusts said deflecting plate through said discharge opening and permits it to be returned to normal position by said counterweight; and said safety door is thrust open to discharge exterior to said fitting any surplus conveyed material held in said fitting.

3. In a conveyer device, the combination with a casing having a discharge opening at one end thereof and a safety opening in spaced relation with said discharge opening; of an endless chain conveyer mounted in said casing; means for supporting and driving said chain; a series of buckets on said chain for dumping the material conveyed through said discharge opening; a lever having a fulcrum at one end and a deflecting plate at the other end; means for supporting said fulcrum in said casing with said deflecting plate adjacent the lower end of said discharge opening and in co-operative relation with said safety opening; means on said lever for normally maintaining said deflecting plate in a predetermined position with respect to said discharge opening and the path of traverse of the buckets on said chain; said lever being adapted to be encountered by said buckets in succession; whereby operation of said chain causes the material discharged by said buckets to be deflected from said casing through said opening, and thrusts said deflecting plate through said opening to discharge material therefrom, through said safety opening when the material accumulates in the space between said discharge opening and safety opening.

4. In a conveyer device, the combination with a casing having a discharge outlet and a safety

opening in spaced relation with said outlet; of an endless chain conveyer mounted in said casing; a series of buckets on said chain for dumping the material conveyed through said outlet; a lever having a fulcrum at one end and a deflecting plate at the other end; means for supporting said fulcrum in said casing with said deflecting plate extending across said outlet and in cooperative relation with said safety opening; and a counterbalance weight on said lever for normally maintaining said deflecting plate in position to deflect said material through said outlet; said lever having a cam element presented toward said chain and adapted to be encountered by said buckets in succession; to oscillate said deflecting plate in said outlet, and discharge material therefrom, through said safety opening when the material accumulates in the space between said outlet and safety opening.

5. In a conveyer device, the combination with a casing having a discharge outlet and a safety

opening in spaced relation with said outlet; of an endless chain conveyer mounted in said casing; a series of buckets on said chain for dumping the material conveyed through said outlet; a lever having a fulcrum at one end and a deflecting plate at the other end; means for supporting said fulcrum in said casing with said deflecting plate extending across said outlet and in cooperative relation with said safety opening; and means on said lever for normally maintaining said deflecting plate in position to deflect said material through said outlet; said lever having a cam element presented toward said chain and adapted to be encountered by said buckets in succession; to oscillate said deflecting plate in said outlet, 10 and discharge material therefrom, through said safety opening when the material accumulates in the space between said outlet and safety opening.

CHARLES G. O'HARA. 20
